UNITED STATES PATENT OFFICE

WILL EVANS, OF HERMOSA BEACH, CALIFORNIA

MOP HANDLE STRUCTURE

Application filed January 21, 1930. Serial No. 422,321.

My present invention relates to a mop handle structure, and particularly to handle structures for mops used for mopping floors and the like.

detail and particularly set forth in the appended claims, reference being had to the accompanying drawing and to the characters of reference thereon which form a part of this application in which:

Figure 1 is a perspective view of a wringer mop incorporating my invention; Fig. 2 is an enlarged perspective view of the wringer crank or handle retaining member shown in Fig. 1, but separate and apart from the other parts of the mop; and, Fig. 3 is a perspective view of a slightly modified form of construction of the retaining member shown in Fig. 2.

Like characters of reference refer to similar parts and portions throughout the views of the drawing.

The mop shown in the drawing consists substantially of a base or foot plate 1 to the upper side of which is pivotally connected the one end of a handle 2, a mop cloth 3 looped around the forward end 1a of the plate 1, a wringer 4 to which the opposite end of the mop cloth is fastened, and a wringer retaining member 5 mounted on the handle 2.

The wringer 4 consists of a wire member having a bearing portion 4a intermediate its ends which extends transversely through the handle 2. At the end of the bearing portion 4a extending to the under side of the handle is a loop portion 4b which extends transversely of the bearing portions and supports said opposite end of the mop cloth at the back side of the base plate 1 at the under side of the handle. To the opposite or upper end of the bearing portion 4a is secured a crank 4c to the end of which is fitted a knob 4d for rotating the crank when desiring to wring the mop cloth.

The handle 2, which is one of the features of novelty in my mop, consists of a long, slender piece of wood of substantially the normal length and diameter of mop handles. The cross section of the handle is polygonal preferably of such number of sides so that the handle may be gripped tightly and prevented

5 The objects of my invention are: first, to provide a handle for mops whereby the mop may be easily held, twisted, or otherwise manipulated, and a handle which does not slip readily in the hands of the operator when the hands are wet, soapy, or slippery from other causes; second, to provide means in connection with a mop in which the mop cloth is wrung by a wringer on the mop, whereby the handle or crank of the wringer may be held in a fixed position; third, to provide such wringer cranks or handle retaining means in connection with a handle of polygonal cross section or one which is longitudinally ribbed so that the retaining means 50

10 may be readily shifted longitudinally with respect to the handle without turning with respect to the handle; fourth, to provide a wringer crank or handle retaining means which is held on the handle by frictional engagement by reason of the inherent resiliency of the means and without auxiliary securing means; fifth, to provide such wringer crank or handle retaining means which may be 55 readily attached to the handle and readily operated for retaining the wringer crank or handle in a fixed position relative to the handle of the mop; sixth, to provide as a whole a novelly constructed mop handle structure of the class mentioned; and, seventh, to provide a mop handle and also a wringer crank retaining means in connection therewith which are simple and economical of construction, light of weight, durable, and which will not readily deteriorate or get out 60 of order.

With these and other objects in view, as will appear hereinafter, my invention consists of certain novel features of construction, combination and arrangement of parts and portions, as will be hereinafter described in

from turning in the hand even though the hand is soapy or slippery from other causes. The number of sides is also sufficiently great that the intersecting sides form edges which are not sharp and not hard on the hand. In the drawing I have shown a handle with eight sides, that is, of octagonal cross section, which satisfies the requirements above mentioned.

16 The wringer crank positioning or retaining member 5, shown in Figs. 1 and 2, is made of sheet metal, (preferably brass) which is so shaped that it extends substantially around the handle, and is held in the desired position thereon by friction caused by bending the member in such manner that the legs 5a at the opposite sides are resilient and resiliently engage the opposite sides of the handle. The body of the member 5 conforms in shape to the shape of the exterior of the handle, and, as shown in the drawing, engages all but the lower sides of the handle. The upper side of the member 5, which is the upper facet, is slightly longer and is turned upwardly at its ends, forming upwardly extending ears 5b and 5c. The ear 5b is provided at its upper edge with a notch 5d into which the crank 4c of the wringer is adapted to extend when the member 5 is shifted under the crank portion on the handle 2, or when the crank 4c is rotated and raised into the notch. The ear 5c provides a grip whereby the member 5 may be readily shifted longitudinally on and with respect to the handle 2.

17 The retaining member 5, shown in the modified form in Fig. 3, is made of a band of resilient metal of uniform width. The legs 5a engage resiliently the opposite sides of the handle as in the structure above described and shown in Figs. 1 and 2. For the upper facet in the structure described above is substituted a bridged portion which consists of a V-shaped channel 5e having downwardly extending leg portions 5f from which the legs 5a extend. In this instance the crank 5c extends into the channel portion 5e. The legs in the modified structure are also more resilient with respect to each other than in the other structure.

18 Though I have shown and described a particular construction, combination and arrangement of parts and portions, and a certain modification thereof, I do not wish to be limited to this particular construction, modification and arrangement, nor to the modification, but desire to include in the scope of my invention the construction, combination, and arrangement substantially as set forth in the appended claims.

Having thus described my invention, what I claim as new and desire to secure by Letters Patent is:

1. In a mop of the class described, a long slender longitudinally ridged handle, a mop

secured at one end thereof, a crank means inserted transversely through the handle, and a ridged crank retaining member slidably mounted on the longitudinally ridged handle adapted to retain the crank means in a fixed position relative to the handle, said crank retaining member comprising a yieldable and resilient band partially surrounding the longitudinally rigid handle and having rigid means at its outer side for receiving the crank portion of the crank means for holding the same with respect to the ridged handle when the member is shifted along the handle.

2. In a mop of the class described, a mop handle, a mop foot secured thereto, a mop cloth extending around the foot, a wringer mounted on the handle and connected to one end of the mop cloth, said wringer having a crank portion, and a retaining member slidably and non-rotatably mounted on the handle, said retaining member comprising a yieldable and resilient band partially surrounding the handle and having rigid means at its outer side for receiving the crank portion of the wringer for holding the crank portion from rotating with respect to the handle when the member is shifted along the handle.

3. In a mop of the class described, a mop foot, a handle of polygonal cross section pivotally connected at one end to the mop foot, a mop cloth extending around the lower side of the foot, a wringer rotatably mounted on the handle on an axis transverse to the handle and connected at one end to the mop cloth and provided at the opposite end with a crank portion, and a slide reciprocally mounted on the handle, said slide comprising a resilient band separated at its ends and partially surrounding the handle, said band conforming substantially to the polygonal cross section of the handle and yieldably engaging the sides thereof, the portion of the band intermediate the separated ends thereof being provided at one end with an upwardly turned lug having a recess in its end adapted to receive the crank portion of the wringer when the slide is shifted toward the axis of the wringer.

4. In a mop of the class described, a mop foot, a handle of polygonal cross section pivotally connected at one end to the mop foot, a mop cloth extending around the lower side of the foot, a wringer rotatably mounted on the handle on an axis transverse to the handle and connected at one end to the mop cloth and provided at the opposite end with a crank portion, and a slide reciprocally mounted on the handle, said slide comprising a resilient band separated at its ends and partially surrounding the handle, said band conforming substantially to the polygonal cross section of the handle and yieldably engaging the sides thereof, the portion of the band intermediate the separated ends thereof being

provided at one end with an upwardly turned lug having a recess in its upper end adapted to receive the crank portion of the wringer when the slide is shifted toward the axis of the wringer, the opposite end of the intermediate portion of the band being provided with a second upwardly turned lug to facilitate the shifting of the slide.

In testimony whereof, I have hereunto set my hand at Los Angeles, California this 7th day of January, 1930.

WILL EVANS.
